UNITED STATES PATENT OFFICE

168,812

FLUORESCENT LIGHTING FIXTURE

James K. Ulrick, Groesbeck, Ohio

Application October 30, 1952, Serial No. 22,048

Term of patent 14 years

(Cl. D48—23)

To all whom it may concern:

Be it known that I, James K. Ulrick, a citizen of the United States, residing at Groesbeck, Colerain Township, county of Hamilton, and State of Ohio, have invented a new, original, and ornamental Design for a Fluorescent Lighting Fixture, of which the following is a specification, reference being had to the accompanying drawings, forming part thereof.

Fig. 1 is a perspective view of a fluorescent lighting fixture showing my new design.

Fig. 2 is a bottom plan view thereof.

Fig. 3 is a top plan view; and

Fig. 4 is an end elevational view.

I claim:

The ornamental design for a fluorescent lighting fixture, as shown.

JAMES K. ULRICK.
